UNITED STATES PATENT OFFICE

2,474,860

POWDER DISPENSING TOOTHBRUSH
HOLDER

Ludwig F. Perwas, Bronx, N. Y.

Application March 8, 1946, Serial No. 652,874

3 Claims. (Cl. 132—84.2)

1

This invention relates to a dispenser that can be attached to a wall for use in a wash room or bath room or used for a toothbrush.

An object of the invention is to provide a dispenser that is efficient in operation and will readily dispense dentifrice into the palm of the user for application to a toothbrush with which the container is used or a conventional toothbrush.

The toothbrush and container is attractive in design and capable of carrying an adequate supply of dentifrice and the wall dispenser can be made of any size or shape desired.

With the above and other objects and advantages in view the invention consists of the novel details of construction, arrangement and combination of parts more fully hereinafter described, claimed and illustrated in the accompanying drawing in which:

Figure 1 is a side elevation of the dispenser as applied to the toothbrush shown in section;

Figure 2 is a sectional view of the dispenser and toothbrush; and

Figure 3 is a sectional view on the line 3—3 of Figure 1.

Referring more in detail to the drawing the reference numeral 10 designates the body or handle having the removable brush head 12 mounted therein or the head may be fixed in the body in some suitable manner. A removable cover 14 is provided for the head 12 and mounted on the body protects the head from dirt.

The elements previously described are oval in cross section for easy grasping thereof.

Formed in the body 10 adjacent the bottom thereof are the ribs 16 having threaded edges 18 to receive the anchor nut 20 and the side of the body 10 are threaded at 22 to conform to the nut 20 and a lock washer 24 secures the anchor nut 20 in position.

The anchor nut 20 is provided with a threaded bore 26 to receive the externally threaded housing or dispenser 28 but the washer 24 is provided with a smooth bore 30.

The housing 28 is provided with the dispensing slots 32 of which there are four in number and are oppositely positioned with relation to each other.

Below the threads 18 the body is provided with shoulders 34 which engage the gasket 36 on the plate 38.

Below the slots 32 the housing 28 is provided with threads to receive the cap 40 and a perforated retainer 42 is seated in the cap and contacts the ends of the housing 28 when the cap 55

2

40 is in position. This retainer prevents an excessive ejection of the dentifrice.

An ejection plug 44 having a seat 46 therein to receive the spring 48 is mounted in the housing 28, and is provided with a hollow stem 50 having a threaded end 52 adapted for engagement with the threaded bore 54 of the cap 40 and a knurled end 56 thereon. The passage 58 in the stem permits the escape of air therefrom and the end 56 is apertured at 60 for the release of the air passing through passage 58.

A retainer 62 loosely attaches plate 38 to the dispenser 28 to avoid having to hold independent parts when refilling the supply chamber 64. 15 There is sufficient space between retainer 62 and plate 38 to permit the dispenser unit to turn as plate 38 remains stationary. The distance of the threads on the dispenser 28 will determine the space.

20 To operate for refilling, remove the dispenser 28 which removes plate 38 by means of the retainer 62. Pour dentifrice into chamber 64 until it reaches the level of the anchor nut 20. Then replace the dispensing unit and plate 38. To 25 dispense the dentifrice unscrew plug 44 by means of end 56 and push it in and out holding the body in an upright position. After obtaining a sufficient quantity of dentifrice the plug is replaced and the bottom cover 66 is placed on the end of 30 the body.

The spring 48 and the end of the plug 44 having the seat 46 therein may be eliminated and the dentifrice shaken into the palm of the hand for the use thereof, and the retainer 62 may be 35 omitted as well as the lockwasher 24 by cementing the anchor nut 20 to the body 10.

It is believed that the operation and construction of the device will be apparent to those skilled in the art and it is to be understood that changes 40 in the details of construction, arrangement and combination of parts may be resorted to without departing from the spirit of the invention or the scope of the appended claims.

Having thus described the invention what is 45 claimed as new and desired to be secured by Letters Patent is:

1. In a toothbrush, an elongated substantially hollow handle oval shape in cross section, a brush head mounted in one end of the handle and extending therefrom, a cap also oval shape in cross section covering the brush head and frictionally mounted on the handle, a cover removably mounted in the opposite end of the handle, said handle having ribs with threaded inner edges spaced from the end thereof in which the cover is

mounted, a pump housing with openings in the walls thereof positioned in said handle, means removably mounting the pump housing in the said ribs, a piston having a tubular stem positioned in said housing, a perforated head on the outer end of the piston stem and a cap on the outer end of the pump housing providing guide means for the piston stem.

2. In a toothbrush as described in claim 1, resilient means in the pump housing urging the piston outwardly.

3. A toothbrush as described in claim 1, in which the means mounting the pump housing in the ribs comprises a threaded nut in which the said pump housing is threaded.

LUDWIG F. PERWAS.
